GUN PERFORATOR FOR WELL CASINGS

Ira J. McCullough, Los Angeles, Calif.

Application November 14, 1939, Serial No. 304,333

19 Claims. (Cl. 164—0.5)

My invention relates to the art of perforating well casing after it has been set in a well and relates in particular to a well casing perforating gun which is of simple form and may be readily manufactured in a form wherein the gun bores for receiving the projectiles are placed relatively close together and wherein all operations necessary for charging and recharging, renewal of worn parts, etc., may be performed without dismantling the gun body, but merely by removal of threaded members which screw into lateral openings in the gun body.

The present invention constitutes an improvement over the disclosure of U. S. Patent No. 2,154,859 granted to me April 18, 1939, for Gun perforator and method, wherein there is a disclosure of the manner in which a plurality of charges of explosive in the chambers connected to gun bores may be fired by conducting to the charges of explosive through small ports or restraining openings, the flame or heat and pressure resulting from the explosion of an ignition charge.

It is an object of the present invention to provide a simple arrangement in a perforator gun body whereby the series firing of a progression of explosive charges, associated with gun bores containing projectiles may be accomplished. In the present invention part of the flame, heat and/or pressure from the burning of one firing charge is passed through a restraining means to the succeeding firing charge to ignite the same, with the result that the ignition of one firing charge, preferably at the top of the gun body but not necessarily so, results in the series firing of the remaining firing charges in the gun body.

In the present invention, the chambers for the firing charges are connected in series by ports or passages which are of such size as to permit passage of a flame from the explosion of one firing charge to the next firing charge chamber to ignite the firing charge therein, but which ports or passages are of such limited size that the reverse flow of explosion products will be restrained to such small value that the loss of explosive pressure through the ports or passages will not be great enough to prevent an effective discharge of the projectiles from the gun bores. These ports or passages become enlarged after a period of use by the burning action of the flame and explosion products which pass therethrough, and before the size thereof is increased to such an extent as to interfere with the proper action of the gun, they must be reconditioned or renewed.

It is an object of my present invention to provide a series of firing charge chambers in a gun body, each of which firing charge chambers is accessible through the side wall of a gun body when an associated closure member is removed from the side of the gun body, passages serially connecting the firing charge chambers and removable and replaceable restraining means insertable in the passages through openings which lead into the gun body from the side wall thereof.

In the present invention, series connection of the firing charge chambers is accomplished through interconnecting passages having restraining means therein and replacement or renewal of projectiles, firing charges, and restraining means may be accomplished through the side wall of the gun body without the necessity of dismantling the gun body, this dismantling being shown in my patent, No. 2,218,802, granted October 22, 1940, for Gun perforator, which discloses a gun body comprised of body sections connected in end to end relation and having gun bores with firing charge chambers which are connected in series through the interconnecting ends of the body sections.

It is an object of the invention to provide a gun body having a plurality of longitudinally spaced firing charge chambers for holding charges of explosives in operative relation to gun bores, openings extending into the body in positions between the firing charge chambers, passages extending from inner portions of these openings to the adjacent firing charge chambers and replaceable restraining means secured in the openings to connect the passages in series.

It is an object of the invention to provide a gun body of the character set forth in the preceding paragraph wherein the firing charge chambers are located at the inner ends of bores which receive removable gun barrels. In the use of this construction the gun barrels may be unscrewed from their positions of operation so that the firing charges may be placed in the firing charge chambers, after which reinsertion of the gun barrels with new projectiles in place therein, results in closing the firing charge chambers. The restraining means in the radial openings between the firing charge chambers ordinarily comprise threaded pins or screws which may be readily unscrewed and removed from the side of the gun body for purpose of inspection or replacement when required.

A further object of the invention is to provide a perforating gun of the general character hereinabove set forth, having also an initial ignition

element which is insertable from the side wall of the gun body.

A further object is to provide a perforating gun having a firing pin which is sealed in operative position by sealing means which is insertable from the side wall of the gun body.

A further object of the invention is to provide for a perforating gun of the character described a firing pin arrangement having a holder from which a firing pin assembly may be readily removed, this firing pin assembly having an outer permanent bar portion which holds a replaceable pin element subject to wear and destructive action in the normal use of the gun.

Further objects and advantages will be brought out in the following part of the specification.

Referring to the drawings which are for illustrative purposes only:

Fig. 1 is an elevational view of a preferred form of the invention.

Fig. 2 is an enlarged sectional view of the upper portion of the gun.

Fig. 3 is an enlarged partly sectional view of the lower portion of the gun.

Fig. 4 is a cross-section taken as indicated by the line 4-4 of Fig. 2.

Fig. 5 is an enlarged cross-section taken as indicated by the line 5-5 of Fig. 3.

Fig. 6 is an enlarged fragmentary section taken on the plane represented by the line 6-6 of Fig. 5.

In Fig. 1 of the drawings I show a preferred form of my gun perforator as comprising a gun body 10, a firing member 11 secured to the upper end of the gun body 10, a suspension member 12 for connecting the perforating gun to a cable 13, a sleeve 14 surrounding the suspension member 12 and being adapted to receive the impact of a weight member or go-devil 15 which is dropped down along and around the cable 13, means 15 whereby this impact may be transmitted to the firing mechanism of the firing member 11, and a safety lock for the firing mechanism comprising a spring supported dog 16 and actuating means therefor consisting of a member 17 having frictional engagement with the wall of a tube 18 in which the perforating gun may be moved.

As shown in Fig. 2, the firing member 11 includes a cylindrical body 19 from which a stem 20 of reduced diameter extends upwardly. This stem 20 has a bore 21 which leads downward from its upper end and communicates with a transverse opening 22 disposed adjacent the upper end of the body 19. A firing pin bore 23, coaxial with the bore 21, extends downward from the upper end of the body 19 to a recess 24 formed cylindrically on an axis which coincides with a diameter of the body 19, this recess 24 having a smaller recess 25 projecting from the bottom thereof and having a threaded counterbore 26 which is open to a side of the body 19 to removably receive a threaded plug 27. A cylindrical block 28 is held in a recess 24 by means of the plug 27. This block 28 has a projection 29 entering the recess 25 so as to prevent rotation of the block 28. The block 28 has a vertical bore 30 to receive a priming means which may be in the form of a blank cartridge 31 which is held in position to be engaged by a firing pin 32 axially movable in the bore 23. The rightward or front face of the block 28 has a threaded opening 33 into which the threaded end of a pin may be screwed for the purpose of pulling the block

28 from the recess 24 when it is desired to install a priming member 31.

Below the recess 24 in the body 19 there is an igniting charge chamber 34 which communicates with the side of the body 19 through a threaded counterbore 35 adapted to replaceably receive a closure member in the form of a threaded plug 36. An axial opening 37 connects the lower end of the opening 38 of the block 28 with the ignition charge chamber 34, and an axial passage 38 extends downward from the ignition charge chamber 34 to the lower end of the body 19, as shown in the upper part of Fig. 3. The lower end of the body 19 has means for connecting the firing member 11, of which it is a part, with the upper end of the gun body 10. Such means of joinder is shown as a threaded pin 39 which is screwed into a box 40 in the upper end of the gun body 10.

The firing pin 32 has a head 41 disposed in the lateral opening 22 at the lower end of the stem 20, which head 41 is held in tight engagement with the lower end of a vertical bar 42 by means of an internally threaded cup 43, disposed in such position that the upper portion thereof lies in the bore 21 and the lower portion thereof projects down into the lateral opening 22. The upper end of the bore 21 is provided with a threaded counterbore 44 to receive the threaded body 45 at the lower end of the suspension member 12. This threaded body 45 has an axial opening 46 to receive the upper portion 47 of the bar 42, and the bar 42 is provided with a collar 48 which is normally held in engagement with the lower end of the threaded body 45 by a compression spring 49, the lower end of which rests upon a washer 50 removably placed in the bore 21 above the member 43. The lower part of the suspension member 12 has a lateral opening 51 into which the upper portion 47 of the bar 42 projects, and a shear pin 52 is passed through the upper portion 47 of the bar 42 in such position that the projecting ends thereof will lie against the upper face of the threaded body 45. The means 15, shown as a lateral bar, having notches 54 in the ends 53 thereof, is placed in the opening 51 in a position to engage the upper end of the bar 42 and so that the notches 54 at the ends thereof will engage diametrically opposed portions of the lower end of the sleeve 14. Short screws 55 are passed through the wall of the sleeve 14 into engagement with the suspension member 12, to limit the upward movement of the sleeve 14 and frictionally retard its downward movement.

The control member 17 comprises an upper sleeve 56 which slides on the sleeve 14, and a lower sleeve 57 which surrounds and is slidable on the neck or stem 20 of the firing member 11. During the downward movement of the perforating gun through the tube 18, the frictional drag on the bow springs 58 of the member 17, will hold such member 17 in raised position as shown in Fig. 1, the upward movement of the same being limited by a snap ring 59 disposed at the upper end of the stem 20. The dog or lock 16 is supported by a leaf spring 61 which lies in a vertically extended groove 62 in the side wall of the stem 20. This spring 61 holds the dog 16 in a retracted position when the sleeve 57 of the member 17 is raised, as shown in Fig. 1. When the sleeve 57 is in lowered position on the stem 20, as shown in Fig. 2, as the result of the perforating gun being moved upward in the tube 18, such sleeve 57 will force the dog 16 inward in the

lateral opening 22 into the position thereof shown in Fig. 2 wherein the inner portion 63 of the dog 16 will lie under the lower face of the cup member 43 and prevent such downward movement thereof as to bring the lower end of the firing pin 32 into firing engagement with the upper end of the priming member 31. The spring 49 is of such strength as to return the bar 42 to raised position, with the weight of the go-devil 14 applied thereto, so that should there be a misfire the firing pin may be locked in raised position, by lifting the device relative to the control member 17 to cause the sleeve 57 to force the dog 16 into locking position relative to the member 43.

A positive seal for the firing pin bore 23 is provided so that there can be no leakage of fluid into the interior of the gun through this opening 23. Above the recess 24 a diametral bore 64 extends through the body 19 so as to intersect the intermediate portion of the firing pin bore 23. This diametral bore 64 is of materially larger diameter than the firing pin bore 23 and has counterbores 65 at the ends thereof into which plugs 66 are screwed. As shown in Fig. 4, granular type graphited asbestos packing material 67 is placed in the diametral bore 64 thereof so as to effectively seal off around the firing pin 32.

Referring now to Figs. 3, 5, and 6, the gun body 10 is provided with a plurality of firing charge chambers 71, individually indicated as 71a, to 71e, spaced longitudinally of the gun body 10 and being disposed at the inner ends of bores 72 in which projectiles 73 are operatively held so as to be discharged as a result of the burning of firing charges in the respective firing charge chambers 71. In the form of the invention herein shown the projectiles 73 are placed at the inner ends of gun bores 74 in removable gun bodies 75 which are threaded into the bores 72. From the bottom 76 of the box 40 a threaded opening 77 is extended down into communication with the uppermost firing charge chambers 71a, and into this opening 77 a restraining member 78 is screwed, such restraining member having an axial passage or restraining port 79 from end to end thereof through which heat and pressure resulting from the ignition of an ignition charge 80 in the recess 34, Fig. 2, may travel down the passage 38, across the space 81 between the lower end of the plug 39, and the bottom 76 of the box 40 and then through the restraining port 79 into the chamber 71a to ignite a firing charge 82 therein. The explosive force resulting from the burning of this firing charge 82 will drive the associated projectile 73 at high velocity through the gun bore 74 and through the adjacent wall of the casing.

The firing charge chambers 71 are serially connected by means whereby the burning of a firing charge in one of these chambers 71 will result in the ignition of the firing charge in a chamber adjacent thereto, so that the effect of igniting all of the firing charges will progress serially. This is accomplished in the following simple manner. As shown in Fig. 6, passages 83 of relatively small diameter are extended respectively upwardly and downwardly from firing charge chambers 71 and in planes between the adjacent firing charge chambers threaded openings 84 are extended into the body 10 from the side thereof in such positions as to connect the openings or passages 83 which extend from the adjacent firing charge chambers. A restraining member 85 is placed in each of these openings 84, such restraining member being shown in the form of a screw and having a passage 86 of small diameter to connect the

passages 83. Accordingly, the flame, or heat and pressure resulting from the firing of the charge 82 in the chamber 71a of Fig. 3 will be transmitted through a passage 83 and the passage 86 of a restraining member 85 to the next succeeding firing charge chamber, and the ignition effect will be transmitted serially downward from one firing charge chamber 71 to the other until the final or lower firing charge chamber 71e, Fig. 3, is reached.

In order that several of the bodies 10 may be connected in series so as to increase the length of the gun, I have provided the lower end of the body 10 with a threaded pin 39', and have extended an opening 87 from the lower firing charge chamber 71e to the lower end of the pin 39'. A restraining member 78 may be threaded into this opening 87 so that in event several of the sections 10 are connected in serial order, the ignition flame or heat and pressure resulting from the firing of a charge in the lower chamber 71e will be transmitted to the succeeding section of the gun. If a single gun body 10 is employed, the lower end thereof may be closed by a protector cap 88 which is threaded onto the pin 39' as shown in Fig. 3.

It will be noted that the firing charge chambers 71 and the associated bores 72 are placed relatively close together in my simple improved construction and that the gun body may be serviced entirely from the side wall, with the exception that the restraining members 78 are inserted in the extreme ends of the body 10.

A feature of the invention is that the bores 72 are spaced so that the outer ends thereof lie on a helix inscribed along the external face of the body 10. Each bore is oriented at an angle, preferably of 90°, from the bores adjacent thereto as shown in the drawings, and particularly in Fig. 5 which shows the firing charge chamber 71b and 71c disposed in vertical planes arranged at angles of 90°. The passage 83 which leads downward from the firing charge chamber 83 connects with one end of the passage 86 in a restraining member 85 which is placed on a line tangential to a circle inscribed around the axis of the body 10. The other end of this passage 86 connects with the passage 83, shown in dotted lines, which leads downward into the firing charge chamber 71d. Although I prefer to orient the consecutive bores at angles of 90°, other angles may be employed. By use of the general arrangement disclosed in the foregoing, I am able to place a maximum number of gun bores and associated firing charge chambers in a gun body of given length, without the necessity of increasing the diametral dimension of the gun body, and to effectively accomplish a serial firing of the charges in the firing charge chambers without dividing any given gun body unit into disjoinable sections.

I claim as my invention:

1. In a perforating gun of the character described, the combination of: a gun body having a plurality of gun bores spaced longitudinally thereof, a plurality of firing charge chambers longitudinally spaced therein and having operative connection with said gun bores, passage means serially connecting said firing charge chambers, there being side openings connecting said passage means with the exterior through the side wall of said gun body; firing charges in said firing charge chambers; projectiles in said gun bores; means for firing at least one of said firing

charges; and restraining means inserted in said passage means through said side openings.

2. In a perforating gun of the character described, the combination of: a gun body having a plurality of gun bores spaced longitudinally thereof, a plurality of firing charge chambers longitudinally spaced therein and having operative connection with said gun bores, passage means serially connecting said firing charge chambers, there being side openings connecting said passage means with the exterior through the side wall of said gun body; and restraining means inserted in said passage means through said side openings.

3. In a perforating gun of the character described, the combination of: a gun body having a plurality of gun bores spaced longitudinally thereof, a plurality of firing charge chambers longitudinally spaced therein and having operative connection with said gun bores, openings extending into said body from the side thereof in positions between said firing charge chambers and having connection with the firing charge chambers lying adjacent thereto, whereby to form passages connecting said firing charge chambers; firing charges in said firing charge chambers; projectiles in said gun bores; means for firing at least one of said firing charges; and restraining means securable in said openings from the outer ends thereof so as to lie in said passages connecting said firing charge chambers.

4. In a perforating gun of the character described, the combination of: a gun body having a plurality of firing charge chambers longitudinally spaced therein and having operative connection with said gun bores, openings extending into said body from the side thereof in positions between said firing charge chambers and having connection with the firing charge chambers lying adjacent thereto, whereby to form passages connecting said firing charge chambers; and restraining means securable in said openings from the outer ends thereof so as to lie in said passages connecting said firing charge chambers.

5. In a perforating gun of the character described, the combination of: a gun body having a plurality of bores extending in from the side wall thereof, the inner ends of said bores forming firing charge chambers, removable means to close said bores, there being gun bores with their inner ends connected to said firing charge chambers, and passage means serially connecting said firing charge chambers, said passage means having side openings connecting them with the exterior of said gun body; and restraining means inserted in said passage means through said side openings thereof.

6. In a perforating gun of the character described, the combination of: a gun body having a plurality of bores extending in from the side wall thereof, the inner ends of said bores forming firing charge chambers, and passage means connecting said firing charge chambers, said passage means having side openings connecting them with the exterior of said gun body; gun barrels removably secured in said bores to hold projectiles in position to close said firing charge chambers; and restraining means inserted in said passage means through said side openings thereof.

7. In a perforating gun of the character described, the combination of: a gun body having a plurality of bores extending in from the side wall thereof, the inner ends of said bores forming firing charge chambers, openings extending into

said body from the side thereof in positions between said firing charge chambers, the inner portions of said openings being connected to the firing charge chambers lying respectively adjacent thereto so as to provide passage means serially connecting said firing charge chambers; gun barrels secured in said bores to hold projectiles and to close said firing charge chambers; and restraining means inserted in said openings so as to lie in said passage means in serial order between said firing charge chambers.

8. In a perforating gun of the character described, the combination of: a gun body having a plurality of gun bores, a plurality of firing charge chambers in operative connection with said gun bores, passage means serially connecting said firing charge chambers, said passage means having side openings connecting them with the exterior of said gun body, and a recess extending into said gun body from the side thereof, said recess having communication with one of said firing charge chambers; restraining means inserted in said passage means through said side openings thereof; firing means inserted in said recess from the side of said gun body; and removable means to close said recess.

9. In a perforating gun of the character described, the combination of: a gun body having a plurality of bores extending in from the side wall thereof, the inner ends of said bores forming firing charge chambers, a recess extending into said body from a side thereof, said recess having communication with at least one of said firing charge chambers, and passage means connecting said firing charge chambers, said passage means having side openings connecting them with the exterior of said gun body; gun barrels removably secured in said bores to hold projectiles in position to close said firing charge chambers; firing means inserted in said recess from the side of said gun body; removable means to close said recess; and restraining means inserted in said passage means through said side openings thereof.

10. In a perforating gun of the character described, the combination of: a gun body having a plurality of bores extending in from the side wall thereof, the inner ends of said bores forming firing charge chambers, a recess extending into said body from a side thereof, said recess having communication with at least one of said firing charge chambers, and passage means connecting said firing charge chambers, said passage means having side openings connecting them with the exterior of said gun body; gun barrels removably secured in said bores to hold projectiles in position to close said firing charge chambers; a holder for a firing means inserted in said recess from the side of said gun body; means operative to actuate said firing means; removable means to close said recess; and restraining means inserted in said passage means through said side openings thereof.

11. In a perforating gun of the character described, the combination of: a gun body having a plurality of bores extending in from the side wall thereof, the inner ends of said bores forming firing charge chambers, a recess extending into said body from a side thereof, said recess having communication with at least one of said firing charge chambers, and passage means connecting said firing charge chambers, said passage means having side openings connecting them with the exterior of said gun body; gun barrels removably secured in said bores to hold projectiles in posi-

tion to close said firing charge chambers; a firing means holder inserted in said recess from the side of said gun body; a firing pin extending into said recess; means operative to actuate said firing pin; removable means to close said recess; and restraining means inserted in said passage means through said side openings thereof.

12. In a perforating gun of the character described, the combination of: a gun body having a plurality of bores extending in from the side wall thereof, the inner ends of said bores forming firing charge chambers, a recess extending into said body from a side thereof, said recess having communication with at least one of said firing charge chambers, and passage means connecting said firing charge chambers, said passage means having side openings connecting them with the exterior of said gun body; gun barrels removably secured in said bores to hold projectiles in position to close said firing charge chambers; a firing means holder inserted in said recess from the side of said gun body; a firing pin extending into said recess; means operative to actuate said firing pin; removable means to close said recess; restraining means inserted in said passage means through said side openings thereof; and sealing means for said firing pin insertable into position to engage said firing pin from the side of said gun body.

13. In a perforating gun of the character described, the combination of: a gun body having a plurality of bores extending in from the side wall thereof, the inner ends of said bores forming firing charge chambers, a recess extending into said body from a side thereof, said recess having communication with at least one of said firing charge chambers, and passage means connecting said firing charge chambers, said passage means having side openings connecting them with the exterior of said gun body; gun barrels removably secured in said bores to hold projectiles in position to close said firing charge chambers; a firing means holder inserted in said recess from the side of said gun body; a firing pin extending into said recess; means operative to actuate said firing pin; removable means to close said recess; restraining means inserted in said passage means through said side openings thereof; sealing means carried by said gun body in a position to seal around said firing pin; and means operative from a side of said gun body to apply pressure to said sealing means.

14. In a perforating gun of the character described, the combination of: an upper gun body section having a firing pin extending down into the upper end thereof, sealing means carried by said body for sealing around said pin and a recess receiving the lower end of said firing pin, said recess opening to the exterior of said body through the side wall thereof; firing means insertable in said recess from the side of said gun body; removable means to close said recess; means operative through the side of said gun body to apply pressure to said sealing means; and perforating means connected to said body section having a gun bore, a firing charge associated with the gun bore to be fired by said firing means and a projectile in said gun bore.

15. In a perforating gun of the character described, the combination of: an upper gun body

section having a firing pin opening extending down into the upper end thereof, a passage extending from the side of said body section and crossing said pin opening, and a recess receiving the lower end of said firing pin, said recess opening to the exterior of said body through the side wall thereof; firing means insertable in said recess from the side of said gun body; removable means to close said recess; a firing pin passing through said pin opening into said recess; sealing means for said pin inserted in said passage from the side of said gun body section; means to close the outer end of said passage; and perforating means connected to said body section having a gun bore, a firing charge associated with the gun bore to be fired by said firing means and a projectile in said gun bore.

16. In a perforating gun of the character described, the combination of: an upper gun body section having a firing pin opening extending down into the upper end thereof, a passage extending from side to side of said body section and crossing said pin opening, and a recess receiving the lower end of said firing pin, said recess opening to the exterior of said body through the side wall thereof; firing means insertable in said recess from the side of said gun body; removable means to close said recess; a firing pin passing through said pin opening into said recess; sectional sealing means passed into engagement with said firing pin from opposite ends of said passage; means operative through the opposite ends of said passage to apply pressure to the said sealing means; and perforating means connected to said body section having a gun bore, a firing charge associated with the gun bore to be fired by said firing means and a projectile in said gun bore.

17. In a perforating gun of the character described, the combination of: a gun body having a plurality of spaced gun bores, a plurality of spaced firing charge chambers each having operative connection with a gun bore, passage means serially connecting said firing charge chambers, there being side openings connecting said passage means with the exterior through the side wall of said gun body; and restraining means inserted in said passage means through said side opening.

18. In a perforating gun of the character described, the combination of: a gun body having a gun bore, a firing charge chamber communicating with the inner end of said gun bore, a firing means recess extending into said body from a side thereof and having communication with said firing charge chamber; means to close said recess; and means for causing actuation of a firing means in said recess.

19. In a perforating gun of the character described, the combination of: a gun body having a gun bore, a firing charge chamber communicating with the inner end of said gun bore, a firing means recess extending into said body from a side thereof and having communication with said firing charge chamber; a firing means holder inserted in said recess from a side of said body; a firing pin extensible into said recess; means operative to actuate said firing pin; and removable means to close said recess.
